(57) **CLAIM**

I claim the ornamental design for a buck yard figure, as shown and described.

DESCRIPTION

FIG. 1 is a left-side view of a buck yard figure illustrating my new design;

FIG. 2 is a right-side view thereof;

FIG. 3 is a front view thereof;

FIG. 4 is a rear view thereof;

FIG. 5 is a top view thereof;

FIG. 6 is a bottom view thereof;

FIG. 7 is a perspective view of a second embodiment of a buck yard figure illustrating my design;

FIG. 8 is a left-side view thereof;

FIG. 9 is a right-side view thereof;

FIG. 10 is a front view thereof;

FIG. 11 is a back view thereof;

FIG. 12 is a top view thereof; and,

FIG. 13 is a bottom view thereof.

The small circles on the body of the buck depict lights that are positioned to illuminate the interior and exterior body of the buck.
